UNITED STATES PATENT OFFICE.

HENRY TURNER, OF RICHMOND, VIRGINIA.

CADDY FOR PACKING TOBACCO.

1,255,954.

Specification of Letters Patent. Patented Feb. 12, 1918.

Application filed October 31, 1914. Serial No. 869,686.

To all whom it may concern:

Be it known that I, HENRY TURNER, a subject of the King of Great Britain, residing at Richmond, in the county of Henrico and State of Virginia, have invented certain new and useful Improvements in Caddies for Packing Tobacco; and I do hereby declare the following to be a full, clear, and exact description of the invention, such as will enable others skilled in the art to which it appertains to make and use the same.

This invention relates to caddies for packing tobacco, and one of the principal objects of the invention, is to provide means of simple construction for giving the end plugs in a caddy the appearance of the plugs packed in the middle of the caddy.

In packing plug tobacco in caddies, the plugs which are disposed adjacent to the wooden ends of the caddy usually have a smooth surface, which is regarded with disfavor by purchasers, and thus the dealer in tobacco is oftentimes required to lose the sale of these end plugs.

My present invention is designed to give the end plugs the same appearance as the middle plugs, and without material expense.

The foregoing and other objects may be attained by means of the construction illustrated in the accompanying drawing, in which,

Figure 1 is a view of the inner side of one of the covers or end members of the caddy, and

Fig. 2 is a sectional view through the caddy with the end members at the top and bottom secured in place to form roughened end plugs.

Referring to the drawing the numeral 1 designates the plugs of tobacco contained within a caddy 2, and 3 are the covers or end members of the caddy. The caddy and covers or ends are usually made of strong wood like oak, and these end members have their inner sides roughened as shown in the drawing. If desired, tobacco leaves 5 may be

secured to the roughened inner sides of the end members by an adhesive substance 4. The end members 3 may be provided with a score line or ridge 6 to represent or to give the appearance of two plugs of tobacco. When the tobacco has been packed in the caddy and the ends 3 have been placed therein the ends 3 are secured in place by binding strips 7, preferably of triangular cross section and said binding strips being nailed in place to hold the tobacco firmly in the caddy.

From the foregoing it will be obvious that the upper plugs *a* and the lower plugs *b* will have upon their outer surfaces the impression of the roughened end members, or of the tobacco leaves 5, so that they cannot be detected from any one of the plugs 1 intermediate the end plugs.

Certain changes may be made in the details of construction without departing from the spirit and scope of the invention as defined in the claim.

What is claimed is:—

A cover or head for tobacco caddies, said cover or head consisting of a piece of hard wood having a smooth outer face and a roughened inner face formed directly in the hard wood to simulate the appearance of a plurality of plugs of tobacco, said roughened inner face forming a bearing surface for the end plugs, and tobacco leaves secured by adhesive material to the roughened face of the said cover or head for directly engaging the end plugs of tobacco whereby the outer face of the end layer will be caused to present the same appearance as the intermediate layers without being affected by contact with the wood.

In testimony whereof I affix my signature in presence of two witnesses.

HENRY TURNER.
